UNITED STATES PATENT OFFICE.

RICHARD J. McCARTY, OF KANSAS CITY, MISSOURI.

RAILROAD-RAIL JOINT.

SPECIFICATION forming part of Letters Patent No. 678,006, dated July 9, 1901.

Application filed March 21, 1901. Serial No. 52,226. (No model.)

To all whom it may concern:

Be it known that I, RICHARD J. McCARTY, a citizen of the United States, and a resident of Kansas City, in the county of Jackson and 5 State of Missouri, have invented a certain new and useful Improvement in Railroad-Rail Joints, of which the following is a specification.

The meeting ends of railroad-rails are now generally secured and supported by splice-bars applied to opposite sides of the rails in 10 position to bridge the joints and rest upon at least two cross-ties and secured to the rails by bolts passing through holes in the splice-bars and the webs of the rails. The holes in 15 the parts are sufficiently larger than the bolts so that the bolts may be easily inserted and so as to allow for the expansion and contraction of the rails under changes of temperature; but this contraction and expansion of 20 the rails causes each rail at the joint to slide back and forth between the splice-bars, and this sliding, which takes place between surfaces that are not perfectly smooth and true, will within a short time cause abrasion of 25 points of contact, and thus loosen the joint. Moreover, there is formed in a short time throughout the joint rust, which the sliding motion disintegrates, and this causes additional tendency to loosen the joint. As soon 30 as a joint becomes loose or begins to loosen the stiffness at the joint becomes reduced, undue strains are brought to bear upon the ties supporting the respective rail ends, and said ties sink to an extent causing unevenness in 35 the track and which then rapidly increases under the hammering action of the wheels passing over the impaired joint. The continuous existence of the above-described effects necessitates constant attention to rail- 40 ways at great expense.

My invention aims to counteract at a reasonable expense the aforesaid conditions, and by securing improvements in the permanence and stability of railroad-rail joints reduce the 45 cost of maintenance of way, as will be fully understood upon reference to the accompanying drawings, which represent the preferred embodiment of my invention, and in which—

50 Figure 1 is a horizontal section of a rail-joint in the plane of the bolts; Fig. 2, a ver-

tical section through one of the bolts; Fig. 3, a side elevation with the bolts severed in a plane of the outer faces of a splice-bar. Fig. 4 represents three sections *a*, *b*, and *c* of the 55 bolt, taken, respectively, on the lines *a a*, *b b*, and *c c*, Fig. 2; and Figs. 5 and 6 are two perspective views of the bolt.

A represents the rail ends; *B*, the splice-bars, preferably of the type providing a base- 60 support for the rails, and *C* the cross-ties.

D represents specially-constructed bolts, and *E* are nuts screwed upon both ends of said bolts.

Each splice-bar *B* is provided at one end 65 with two or more tightly-fitting openings *1* and at its other end with two or more loosely-fitting openings *2*, while the rail-webs are provided with tightly-fitting openings *3*. The bolts *D* are formed with tightly-fitting ends 70 *4*, which are preferably driven into the openings *1* of the splice-bars and openings *3* of the rail-webs, and with loosely-fitting ends *5*, that enter the openings *2* of the splice-bars and have such a fit therein as will permit the 75 bolts when moved by the rail to move horizontally in said openings *2*. This fit is preferably made loose only in a horizontal direction by having the loosely-fitting end *5* of the bolt elliptical, for the purposes to be ex- 80 plained. Each bolt is provided with two threaded ends *6*, that receive the nuts *E*. In order that one end of each splice-bar may be locked rigidly and immovably to a rail end, each bolt is provided with a shoulder *7*, that 85 engages the side of the web opposite or away from the tightly-fitting end of the bolt, so that by screwing up the nut *E* on the said tightly-fitting end the splice-bar on that side and at that end may be locked, as described, inde- 90 pendently of the opposite splice-bar or the nut on the opposite loosely-fitting end of the bolt.

One end of each splice-bar being thus rigidly combined with each of the meeting ends of the rails, the other ends of said splice-bars 95 overlap the rail end abutting that which the splice-bar is combined with and rests upon the cross-tie beneath said abutting end. In this way, should the nuts on the loosely-fitting ends of the bolts become loose, each rail will 100 still have its splice-bar practically forming a continuation of the rail and bridging the joint,

so as to distribute the load over a plurality of ties and prevent any one tie being depressed independently of the others.

In the preferred form of bolt shown the 5 horizontal sides of the enlargement forming the shoulder 7 are continued or tapered outwardly toward the loosely-fitting end of the bolt, while the upper and lower portions of said enlargement terminate at a point between the loosely-bolted end of the splice-bar and rail-web. This gives the end of the bolt which projects within the loosely-fitting openings an oval section which prevents the bolt turning in that opening when either nut is 15 screwed up tight. This form of bolt is shown more clearly in Figs. 5 and 6, while its sections on the line *a a* of the tightly-fitting end, the line *b b* of the loosely-fitting end just behind the enlargement 7, and on the line *c c* 20 within the opening 2 may be seen in Fig. 4. This form of bolt has the further advantage of strengthening the shoulder against the tension imposed by the nut on the tightly-fitting end of the bolt and stiffening the section of 25 the bolt against the shearing or bending action of the sliding splice-bar.

I do not limit myself to any particular form of bolt nor any special manner of arranging the parts to be united. The fundamental 30 feature of my invention is rigidly securing each splice-bar by any suitable means at one end to a rail-section to make it practically an extension of said rail, while the other end of each splice-bar extends at least to the next tie 35 or support and is secured with the ordinary sliding action with the abutting rail.

The manner of assembling the parts is as follows: The bolts are inserted in the rail ends by driving their tightly-fitting portions 40 into the holes of the web of the rail until their shoulders are tightly held in contact with said web, similar ends of said bolts projecting in opposite directions in the respective rails. The splice-bars are then successively 45 placed in position to bring their tightly-fitting holes coinciding with and forced over the tightly-fitting bolt ends, and the nuts at the tightly-fitting ends of the bolts are screwed down as firmly as is practicable, and with the 50 assistance of the pressure from the nuts and blows from a hammer the splice-bars are forced to their seats. This being done, the nuts are screwed on loosely-fitting bolt ends and the whole joint made tight. When the 55 joint shall have been completed as above or by other procedure equally practicable, the parts of the splice-bars contiguous to the tightly-fitting ends of the bolts will be rigidly and immovably attached to sides of the 60 respective rails, while the other part of each splice-bar will be free to move longitudinally along the opposing rail end, which it overlaps by reason of the diameters or horizontal dimensions of the bolts securing said overlapping ends of the splice-bars being less than 65 and therefore loosely fitting the horizontal

diameter of the holes in said splice-bar ends. The rigid attachment of one part of each splice-bar to the rail, as aforesaid, is practically equivalent to an extension of the rail 70 itself past the joint to a tie or ties upon which the abutting rail rests. There being no motion between the splice-bar and the rail where this rigid connection is made, the tendency of the nuts on the tightly-fitting bolt 75 ends to work loose will be reduced to a minimum. If the joint is properly applied, the action of rust along the surfaces of rigid movable contact will be practically eliminated. The effect of this will be to constantly preserve in great measure the rigidity of the joint, and thus constantly protect the ties from the bad effects of loose joints. Furthermore, it is evident that in case the 80 nuts at the ends A of the bolt should become 85 loose the rigidity of the joint will be but slightly impaired.

The shape of the intermediate shoulder or enlargement in the bolt is preferably about that shown in the drawings, but may be of 90 any other shape that would be more convenient for manufacture, while still serving the intended purpose. The material of the bolt should be as soft as is consistent with sufficient tensile strength, so that the bolts may 95 be more easily driven into position.

I have shown my invention applied to what is known as a "swinging" joint—that is to say, a joint in which the rails abut between two ties, with a splice-bar extending from one tie to the other, so as to make a rigid extension of each rail to the next tie beyond its end—but it is obvious that my invention is equally applicable to a joint in which the splice-bars extend over more than two ties, 105 and thus provide a rigid extension of the rail to several ties beyond the end of the rail, if desired, which would probably be the case where roads are constructed over the soft material usually encountered in low countries. 110 In the perfect splice-joint and the one which it is the aim of my invention to produce the same rigidity is obtained at the joint as at any other portion of the rail. If the joint is not sufficiently rigid, it will of course go 115 down. On the other hand, if the joint should be made stiffer than the other portion of the rail the middle of the rail will go down, instances of the latter condition having frequently come to notice. In order to approach 120 as nearly as possible to the condition of uniform rigidity at all points in the track, it may be necessary at times to increase the length of the splice-bars, so as to cover more than two ties.

Having thus described my invention, the following is what I claim as new therein and desire to secure by Letters Patent:

1. A rail-joint comprising abutting rail ends and opposed splice-bars resting upon the ties 130 and supporting the rails, and bridging the joint between the rails and each rigidly bolted

at one of its ends to one rail end and having its other end overlapping and slidingly connected to the abutting rail end.

2. In a rail-joint the combination of the abutting rails, the opposed supporting splice-bars bridging the joint between said rails and the bolts passing through said splice-bars and rails; said bolts having tightly-fitting ends passing through the rail-webs and one end of each splice-bar rigidly and immovably connecting said end of each splice-bar to a rail end, and having loosely-fitting ends passing through and slidingly or movably securing the other end of each splice-bar to the abutting rail which it overlaps.

3. In a rail-joint, the combination of abutting rails, opposed supporting splice-bars bridging the joint between said rails, and bolts in the respective rails having shoulders engaging the rail-webs, bolt ends projecting in one direction from said shoulders, passing through and tightly fitting openings in said rail-webs and passing through and tightly fitting openings in an adjacent end of the splice-bar, and rigidly or immovably securing it to the rail, and bolt ends projecting in the other direction from said shoulders passing through and loosely fitting openings in the projecting and overlapping ends of the rigidly-attached splice-bars, thereby slidingly

connecting each of the latter to the abutting rail.

4. In a rail-joint, the combination of the abutting rails, the opposed splice-bars bridging the joint between said rails and bolts securing the respective ends of each splice-bar to the abutting rails, the one movably and the other immovably, the movably-connected end of one splice-bar being opposed to the immovably-connected end of the other splice-bar; said bolts being formed each with an intermediate shoulder engaging the rail-web, and with tightly and loosely fitting ends, projecting in opposite directions from said shoulder and provided with nuts for the purpose set forth.

5. In combination with abutting rails and opposed bridging splice-bars, bolts, each extending through the rails and having its end fitting respectively, tightly and loosely in openings in the splice-bars and secured by nuts on both said ends, and an intermediate shoulder engaging the rail-web in opposition to the nut on the tightly-fitting end and having its loosely-fitting end flattened to secure it against turning.
